United States Patent Office.

JOSEPH OTTNER, OF NEW BRITAIN, ASSIGNOR TO HART MANUFACTURING COMPANY, OF KENSINGTON, CONNECTICUT.

Design No. 4,930, dated May 23, 1871.

DESIGN FOR CUPBOARD-LATCH.

The Schedule referred to in these Letters Patent and making part of the same.

I, JOSEPH OTTNER, of New Britain, in the county of Hartford and State of Connecticut, have invented and produced a new and original Design for a Cupboard-Catch, of which the following is a specification.

The nature of my design is fully represented in the accompanying drawing, to which reference is made, and in which—

Figure 1 is a front elevation of a cupboard-catch of my design, and

Figure 2 is a side elevation of the same.

B designates the body of the catch, and
A the strike.

C is the ordinary knob or handle.

On the sides of the body B (see fig. 2) are raised concave points *a*, having a smooth surface.

Between each of the points *a*, and extending up a short distance from the end of said points, is a convex rib, the surface between said ribs being filled with fine sunken channels.

The front of the catch is configured, as plainly shown in fig. 1, by raised ornamental work, and a rough sunken surface between said ornamental work, the sunken surface being thickly dotted in the drawing, fig. 1.

I claim as my invention—

The design for a cupboard-catch, as shown and described.

JOSEPH OTTNER.
